Primary Examiner — Melody N Brown(74) *Attorney, Agent, or Firm* — CALDERON SAFRAN & WRIGHT P.C.(57) **CLAIM**

The ornamental design for an automobile, as shown and described.

DESCRIPTION

FIG. 1 is a front elevational view of an automobile showing my new design;

FIG. 2 is a front and left side perspective view thereof;

FIG. 3 is a rear and left side perspective view thereof;

FIG. 4 is a left side elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The broken lines illustrate portions of the automobile that form no part of the claimed design.
